BRUSH MACHINE

Alfred C. Griscom, Sandy Hook, Conn., assignor
to The Dairy Specialties, Inc., Sandy Hook,
Conn., a corporation of Connecticut

Application August 20, 1931, Serial No. 558,200

44 Claims. (Cl. 300—2)

This invention relates to new and useful improvements in means and methods of making brushes.

An object of the invention is to provide improved brush making equipment whereby brushes may be produced more rapidly than has been possible with the equipment heretofore in use.

Another object is to provide a machine particularly adapted for making what is known as dairy brushes, although the machine is not necessarily limited to use in making such brushes, and which is adapted to operate substantially automatically to secure bristles to a core in the formation of a brush.

18 A further object is to provide a brush making machine including means for continuously rotating a core and feeding it lengthwise and means for securing bristles to the core as it is rotated and fed.

20 Another object is to provide a brush making machine including means for mixing bristles, as hair and brass, and means for securing the mixed bristles to a core.

An additional object is to provide an improved 25 method of making brushes, the method including the step of continuously rotating a core and feeding the core in one direction and securing bristles to the core as it is rotated and fed.

Other objects and advantages will become apparent as the description proceeds and as the 30 invention is practiced and it is therefore to be understood that the list of objects here given is by no means all inclusive but is given simply to outline some of the more apparent features of the 35 invention.

The invention also comprehends the novel combination, arrangement and construction of parts as hereinafter set forth. Further, it is to be understood that the invention is not limited 40 to the construction and arrangement of parts as herein set forth but includes all such variations and modifications as fall within the spirit of the invention or the scope of the appended 45 claims to which claims reference should be had for a definition of the invention.

In the drawings:

Figure 1 is a front elevational view of the complete machine in accordance with the present invention;

50 Fig. 2 is a plan view of the same;

Fig. 3 is a view partly in plan and partly in section and on an enlarged scale and showing the operation of applying bristles to a core;

Fig. 4 is a sectional view substantially along 55 the line 4—4 of Fig. 3;

Fig. 5 is a view taken substantially along the line 5—5 of Fig. 3;

Fig. 6 is a side elevational view of the wire feeding mechanism;

Fig. 7 is a transverse sectional view of the vertical bristle container and supply means; 5

Fig. 8 is a view partly in elevation and partly in section and showing the piston and cylinder construction and an automatic cut-off adapted to operate to stop the machine when the supply 10 of bristles is nearly used up; and

Fig. 9 is a detail view showing the means for swinging the brush core mandrel toward and from the bristle applying means.

The means and the method of the present invention relates particularly to and is herein disclosed as applied to the securing of bristles to a spirally grooved core by means of a strand of wire. This type of brush is commonly employed by dairies for the cleaning of tubing used in the 15 handling of milk, as in the pasturizing of milk. However, it is to be understood that the invention is not limited to the making of brushes adapted to be used only about dairies since more or less rigid brushes may be provided or manufactured in accordance with the invention and 20 the use to which the brushes, made in accordance with the invention, are put forms no particular part of the invention.

Referring in detail to the drawings the core 30 to which bristles are to be applied or secured by the machine of the present invention and according to the method of the present invention is indicated at 10. As herein shown this core 10 is of metal and is hollow being rolled from a 35 piece of tubing and it is preferred, of course, that the core be of non-corrosive metal and the core is provided with a spiral groove 11 running for substantially the length of the core although at its respective ends the core has non-grooved 40 tubular end portions 12 and 13. (See Fig. 3.)

The grooved core 10 might, of course, be of wood or other material, it being understood that the core is not necessarily of metal or of any particular metal. Further, the present invention does not have any particular relation to the manufacture of this core but relates to the application of bristles to the core in a manner to provide a brush. Before the core is brought to the present machine it is formed and when 50 tubular and of metal as herein shown has secured in one of its ends, as for example the end 13, a metal block 14 internally screw threaded as at 15. At its end 12 the core 10 is open for its entire diameter.

In the application of bristles to the core 10, the latter is preferably continuously rotated and is also fed lengthwise in a direction to have its entire spiral groove pass the feeding station or the point of application of the bristles. For this reason the end 13 of the core is received in a chuck 16 and clamped whereby the core will rotate with the chuck and if desired the chuck may be provided with pins 17 entering notches 5 in the plug 14 to further establish a driving connection.

Extending through the chuck and rotatable therewith is a bar 18 which bar also extends entirely through the core to project beyond the end 12 thereof and disposed about this bar 18 is a sleeve or filler 19 of an internal diameter to snugly receive the bar and of an external diameter to be engaged by the bottom walls of the spiral groove 11 in a manner to brace or reinforce the core. At its inner end this sleeve 19 abuts the block 14 as at 20 and at its outer end the sleeve is enlarged as at 21 so as to be snugly receivable in the end 12 of the core. On its outer end the bar 18 may be screw threaded to receive a nut 22 whereby to clamp the sleeve 19 in place on the bar and to secure the block 14 and the end 13 of the core in the chuck whereby the chuck, the bar 18, the sleeve 19 and the core 10 rotate as a unit.

The chuck 16 is mounted on and turns with and is moved by a feed screw 23 driven by a motor 24. Motor 24 is coupled to drive a shaft 25 carrying a worm 26 and which shaft is mounted in suitable bearings in a bracket 27 secured on a standard or table 28 supported as by means of legs 29. Motor 24 is also mounted on the table 28. Worm 26 meshes with and drives a worm gear 30 mounted on a shaft 31 which shaft has bearing at one end in a bracket 32 and at its other end in the bracket 27. A small pinion or gear 33 is arranged on the shaft 31 and this gear 33 meshes with a relatively large gear 34 secured to the feed screw 23 and having a key operating in the slot or keyway 23a in the screw. A bracket 35 has one end portion 36 disposed on the shaft 31 so as to be turnable thereon and at its end 37 this bracket is threaded and receives the feed screw 23. Bracket 35 also has lateral extensions 38 through which bolts 39 may pass to secure the bracket to similar extensions on an arm 40 also disposed on the feed screw 23 but at the side of the gear 34 opposite that at which the end portion 37 of bracket 35 is disposed. The feed screw may have threaded connection with either the portion 37 of the bracket 35 or the arm 40 whereby as the screw is turned on movement being imparted to the gear 34 the screw will be fed longitudinally so as to feed the core 10 in a lengthwise direction in addition to rotating the core.

Since the end portion 36 of the bracket 35 is turnable on the shaft 31 means are provided for holding the bracket in the desired position relative to the shaft. To this end a quadrant 41 is mounted on the table 28 between the brackets 27 and 32 and is provided with an arcuate surface having notches 42 and 43 each adapted to receive the lower end of a pin 45. Fig. 9 shows the parts in the position occupied by them during the filling 70 of a brush core or during the time that bristles are being applied to a core.

When the core is completely filled it will have been fed lengthwise by or past the filling station and in order that it may be more easily removed 75 from the machine and without damage to the

bristles it is swung laterally away from the filling station. This is accomplished by elevating the pin 45 from the position shown in Fig. 9, that is out of notch 43, and then swinging the gear 34, feed screw 23 and parts carried thereby laterally 5 or outwardly, that is, toward the left as viewed in Fig. 9 and locating the pin 45 in the notch 42. The purpose of this arrangement will appear more fully as the description proceeds.

As before suggested bristles are secured to the core 10 by means of a wire and the mounting and feeding of this wire will now be described. The securing wire is indicated at 46 and is supplied from a spool 47 rotatably mounted on a bolt or pin 48 carried by the upper end portion of an 15 upright 49 supported from the table 28. On leaving the spool 47 the wire 46 is carried about a relatively small friction spool 50 and then by an idler roll 51 to a peripherally toothed bristle feeding means shown as a metering wheel 52 about 20 the core of which the wire is twice passed after which its end is secured to a brush core 10. The end of the wire may be secured to the core 10 in any suitable manner but I prefer that it be secured as by pressing up a portion of the metal 25 of the core between incisions and then passing the end of the wire about the pressed up portion to anchor said end. Since the end of the wire is secured to the core the wire will be pulled from the spool as the core is rotated and fed. 30

The idler roll 51 is pivotally mounted as at 53 to one end portion of a lever 54 which lever is pivoted intermediate its ends as at 55 to one end portion of a cross arm 56 secured to the upright 49 as by screws 57 and carrying the small friction 35 or tension spool 50 before referred to. A coil spring 58 is anchored at one end to a pin 49 carried by the cross arm 56 and at its other end the said spring is secured to a pin or post 60 carried by the lever 54 and acts to have the idler 40 roll apply a tension to the wire. The function of this lever will later be described more in detail but here it may be stated that the lever is used for the purpose of pulling a supply of wire from the supply spool 47 in order to enable the operator 45 to have sufficient free wire available for anchorage to the core.

Means is provided for constantly supplying bristles to the toothed bristle feeding means or metering wheel 52. The supply means includes 50 a receptacle 61 which is somewhat wedge shaped in cross section as shown in Fig. 7 and which includes a rear wall 62 to which inclined side walls 63 and 64 are secured as by means of machine screws 65. A front wall 66 for the receptacle has a strap 67 secured thereto and at one end this strap is secured to a bracket 68 carried by the side wall 63, the pivotal connection being indicated at 69. At its other end the strap 67 is bifurcated to receive a bolt 70 pivoted as at 71 and carrying a wing nut 72 adapted to be tightened to engage the strap 67 and lock the front side 66 of the receptacle in closed position as shown in Fig. 7.

Operating in the receptacle 61 is a follower 65 73 carried at the upper end of a plunger or piston rod 74, which piston rod extends into a cylinder 75 arranged below and in line with the receptacle 61. Within the cylinder 75 the rod 74 carries a piston 76 comprising oppositely disposed cup-like 70 members 77 and 78 clamped between discs 79 on the tightening of a nut 80.

Air under pressure, or for that matter any other fluid pressure, is supplied through a pipe or conduit 81 to a three way valve 82 which valve 75

may be operated to put the pipe 81 into communication either with a branch 83 or a branch 84. When the valve 82 is operated to pass fluid, as air, under pressure to the branch 83 the said fluid under pressure will enter the upper portion of the cylinder 75 and force the piston 76 downwardly therein so as to draw the follower to the bottom of the receptacle 61.

Obviously, if the valve 82 is operated to place the line 81 in communication with the branch 84 fluid under pressure will be admitted to the lower end of the cylinder 75 and engaging the under side of piston 76 will force the same upwardly resulting in the follower 73 being moved toward the upper end of the receptacle 61. Therefore, bristles 85 in the receptacle will be under pressure and will be closely packed and will always be urged toward the upper end of the receptacle.

Convenient operating means is shown for controlling the valve and this means includes a hand lever 86 pivoted intermediate its ends as at 87 and at one end pivotally connected with an end of a link 88 as at 89 and at its other end pivotally connected with an arm 90 of the valve 82 as at 91. Since the valve 82 is located under the table 28 and in the rear of the cylinder 75 it will be obvious that the means just described enables the valve to be more conveniently operated or controlled.

From Fig. 4 it will be apparent that the upper end of the receptacle 61 is but partially closed by a head member or means 92, the said member being open at its upper end and the toothed bristle feeding means 52 being so disposed as to partially enter the receptacle through the means 92. Since during the operation of the machine a continuous and preferably constant pressure is kept on the piston 76 it will be apparent that a pressure is kept on the bristles 85 by the follower 73 since through the medium of the rod 74 the piston and follower are rigidly connected. Therefore, there is a continuous urging of the bristles 85 toward the bristle feeding means or metering wheel 52.

The toothed bristle feeding means or metering wheel 52 includes a shaft 93 having bearings in blocks 94 and 95 arranged at each side of the head member 92 of the receptacle 61 and on said shaft is mounted the feeding means per se which means includes a bobbin-like member including discs or disc-like members 96 and 97 toothed about their periphery and disposed between inclined spacing members 98. It is between the disc-like members 96 and 97 that the wire 46 is led and is twice wrapped about the feeding means between said discs as clearly shown in Fig. 3. Therefore, as the core draws the wire the metering wheel will be rotated to feed the bristles. A gear 99 is secured to the shaft 93 at the outer side of the block 94 and the full function of this gear will later appear.

When loading the machine, that is, when placing a core in the machine, a locking member or finger 100 pivoted to the block 94 as at 101 is swung to dispose its neb 102 between two of the teeth of the gear 99 so as to lock said gear and its shaft and the bristle feeding means against rotation whereby to prevent feeding of bristles. Next, the lever 54 is operated to press its wheel 51 against the wire 46 whereby to draw some of the wire off the supply spool 47, the free end of the wire being held as by a pair of pliers. That is, the operation of the lever as suggested results in slack being left in the wire between the small

spool 50 and the metering wheel or bristle feeding means 52.

The wire must be pulled from the spool 47 since its free end is held as by pliers or the like. The wire being slackened below the small spool 50 its end beyond the feeding means 52 is grasped as by means of a pair of pliers or the like and the wire pulled to dispose a portion of its free end beyond the feeding means. This operation results in a sliding of the wire about the core of 10 the feeding means since such means is held against rotation by the locking piece 100 before referred to.

When sufficient wire has been drawn beyond the feeding means the end of the wire is secured 15 to a core which has been placed in the chuck or the wire may be secured to the core before the core is placed in the chuck and after the core is placed in the chuck the surplus wire may be drawn from the core and cut off. Next, the valve 20 82 is operated to bring about the application of pressure to the bristles 85 and this will result in the bristles being forced upwardly into the spaces between the teeth on the peripheries of the discs 25 96 and 97 of the feeding means.

The motor 24 may then be started (the finger piece 100 having been moved away from the gear 99 to engage the stop pin 144) and this will result in the core 10 being rotated and fed lengthwise and as the core is rotated and fed the wire 46 30 30 will be drawn onto the core. Before the motor 24 is started a few bristles may be fed by hand to start the brush. This is accomplished by rotating the hand wheel 103 on the outer end of shaft 93 carrying the metering wheel. This hand feeding of bristles takes place without rotating the core from the motor and the start of the core may be well filled or loaded.

Movement of the wire will, of course, result in the feeding means or metering wheel 52 being 40 rotated and as the same rotates it will pick up bristles 85 from the upper portion of the receptacle 61 and carry them up under the wire 46 as clearly shown at 104 in Fig. 4. These bristles extend beyond each side of the wire 46 and the wire will press the central portions of the bristles 45 into the spiral groove of the core as clearly shown in Fig. 3.

As the bristles leave the receptacle they pass 50 over a combined guide and guard 105 formed with the upper portion of the front member of the head 92 and including wing-like portions 106 having a space or slot between them. The wire 46 operates through this space between the portions 106 and the upper inner sides of the wings or portions 106 tend to bend or double the bristles into a U-shape, the tension on the wire serving to pull the wire down into the spiral groove in the core 10 and fold the bristles into a U-shape 55 60 (see Fig. 4).

It will be understood that the size of the spaces between the teeth on the discs 96 and 97 controls the amount of bristles carried out of the receptacle or rather the rate at which bristles 65 are carried out of the receptacle and the proportion is preferably such that the folded bristles together with the wire substantially fill the groove in the core whereby when the brush is completed the bristles are quite rigidly held. In Fig. 4 the 70 completed portion of the brush is shown in section for about two-thirds of the distance about the brush, the wire 46 being exposed for this distance and then a portion of the brush is shown looking at the outer side of the bristles the wire 75

being invisible and being disposed in the groove of the core.

The combined guard and guide means 105 has a function in connection with the completed portion 5 of the brush. This function the means performs acting as a guard and by holding certain of the bristles of the completed portion of the brush away from the wire 46 whereby the end portions of such bristles may not be caught beneath the wire and secured in the groove at a point remote from the place where their central portion are secured in the groove. This is clearly 10 illustrated in Fig. 3 where certain of the bristles immediately to the right of the feeding means 15 are shown as bent over and held over by engagement with the outer surface of one of the wing-like members 106 of the guide and guard means 105.

It sometimes happens that the tension on the 20 wire is not sufficient to cause the wire to seat down tightly in the spiral groove 11 of the core. When this happens it is readily apparent in the brush since the bent over portions of the bristles are not disposed parallel but flare out from one 25 another. These bristles, of course, are not tightly held and a manually operated means is provided for pressing the wire into the groove when the tension on the wire is not sufficient to keep it in the groove.

30 This means involves a lever 107 pivoted as at 108 and having an off-set portion 109 carrying a bifurcated member 110 between the arms of which is rotatably mounted a grooved jacking wheel 111 as by means of a bolt or bearing member 112. Pivotaly connected with the lever 107 is a link 113 and secured to a shaft or rod 114 is a link 115, the ends of the links 113 and 115 being pivotally connected as at 116.

Also, secured to the rod 114 is an operating 40 lever 117 and it will be apparent especially from an inspection of Fig. 6 that the links 113 and 115 form a toggle adapted to be operated by the lever 117. When the parts are in their full line position as shown in this figure the wheel 111 will be 45 pressed against the wire 46 in a manner to press the wire toward the bottom wall of the groove 11 of the core 10. In Figs. 4 and 6 the wheel is shown as engaging the wire for this purpose and from an inspection of Fig. 6 it will be apparent 50 that this pressure is applied by forcing the lever 117 in the direction of the core. A reverse movement of the lever will move the parts into the dot and dash line position shown in Fig. 6 where they are out of the way.

55 A safety cut-off means is provided for stopping the machine on the supply of bristles in the receptacle 61 running low. That is, this automatic cut-off means operates before the supply of bristles is completely exhausted. To this end in 60 the line 118 to the motor 24 from a suitable source of supply of electrical energy there is incorporated any suitable switch 119 adapted to be controlled by lever 120 through a rod 121. The receptacle 61 is held spaced above the cylinder 75 as by means of spacing members 122 and the lever or arm 120 is arranged in this space.

The rod 74 near its lower end is notched as at 65 123 and the arm 120 is so positioned that its free end normally engages the rod 74 and will enter 70 said notch on the piston rising a sufficient distance to bring the notch opposite the arm. That is, when the supply of bristles in the receptacle 61 is quite low the piston may move upwardly for substantially the length of the cylinder 75 and 75 it is not until the piston has had considerable

movement that the notch comes opposite the arm. However, the notch does come opposite the arm before all of the bristles are used and when the arm enters the notch it serves to operate to open the switch 119 and thereby open the circuit to the motor 24 and stop the machine.

In its upper surface the follower 73 is provided with a pair of spaced grooves 124 and the receptacle 61 is in its walls provided with opening 125 adapted to align with the grooves 124 when 10 the follower has moved upwardly a distance sufficient to bring the notch 123 opposite the arm 120. Disposed on the frame of the machine so as to be slidable through the openings 125 of the receptacle 61 and through the grooves 124 in the 15 follower are a pair of pins 126. When the machine stops these pins are pushed inwardly so as to be disposed under the bristles remaining in the receptacle and hold them in place against the feeding means. Next, valve 82 is operated to 20 force the piston 76 downwardly and this will result in the follower 73 moving downwardly, the pins 126 supporting the remaining bristles 85.

The front 66 of the receptacle 61 may now be open and an additional supply of bristles 25 disposed in the receptacle on top of the follower 73. The receptacle may then be closed and the position of the valve 82 reversed so as to force the follower upwardly in the receptacle to crowd the new supply of bristles against the underside 30 of the pins 126. When the pins are now withdrawn the new supply of bristles will be forced against the bristles which remain in the receptacle and the machine may be started again. In connection with this mechanism just described it 35 is pointed out that if a brush has been started and the supply of bristles fail all the work done on the brush will be wasted unless the feeding mechanism can be held fully supplied with bristles.

40 That is, assuming that all the bristles in the receptacle were used and a core in the chuck 14 but partly filled the work which had been done would be wasted since near the starting point the brush would be properly filled and as the supply of bristles became less but a few bristles would be applied to the core and if the machine has been left running the wire will simply be wound in the groove 11 without securing any bristles in place. Since the entire operation is 45 stopped with the present mechanism before the supply of bristles is exhausted it will be apparent that when the supply in the receptacle has been replenished a brush which was partially completed when the automatic cut-off went into operation may be completed and that all parts of the brush will be properly filled.

55 It is believed that from the foregoing description the operation of making a brush on the machine and in accordance with one method of the present invention will be clear. However, it is desired to point out that when a core has been filled the feed of bristles is stopped and this stopping may take place automatically as by means of a cam at each end of the feed screw 60 23 to open a switch to the motor 24 when the feed screw has fed the core the desired distance first in one direction and then in the opposite direction. The pin 45 is then raised to swing the filled core away from the feeding means and expose a length of wire between the feeding means and the brush. The wire is secured to the core so as not to lose tension when cut and after it is cut its end is more securely and permanently anchored to the core in any suitable 65 70 75 75

manner to prevent the wire from unwinding and releasing the bristles. It will be appreciated that since the filled core may be swung laterally a length of wire will be exposed and may be cut to provide an end which may be doubled and secured to the core. Of course, if the tension on the wire was released the wire would loosen on the core and release the bristles.

It will be understood that the tensioning means including the roller 111 will be moved to an out of the way position as shown by the dot and dash lines in Fig. 6, before the pin 45 is operated to swing the core away from the feed means. The chuck 16 may now be opened and the nut 22 removed to permit the sleeve 19 and the core 10 to be removed from the machine. Since these parts must be slid off the bar 18 it will be obvious that the brush must be swung laterally away from the feeding mechanism since otherwise its bristles would engage the guide 105, particularly the wing-like portions 106 thereof during the said sliding movement of the brush off the bar 18.

The receptacle 61 may be loaded with any kind of bristles or bristle material, as hairs, brass or the like. Further, the receptacle may be loaded with but one material or with a mixture of materials, it being understood that the feeding means may if desired be modified to adapt it for use with particular types or kinds of materials.

The machine also includes means for mixing the bristles that are applied to the core 10. That is, the bristles applied to the core may be a mixture of hair and brass or German silver or other materials as desired or the bristles may be all of one kind in which event it is best to feed them all from the receptacle 61. When a mixture is desired a bracket 121 is secured in place as shown in Fig. 5 and this bracket includes a gear or carries a gear 128 on a short shaft 129 and the gear 40 128 meshes with the gear 99 and with a gear 130 on a shaft 131 mounted in the blocks 94 and 95 above referred to. The shaft 131 carries a bristle feeding means comprising spaced discs 132 each of which is notched or toothed in its periphery and these discs are so spaced apart and of such diameter as to over-lap the discs 96 and 97 at their outer sides as clearly shown in Figs. 2, 3 and 4.

The discs 132 are arranged to take bristles 133 from a receptacle 134 which is slightly open at its forward end and which is arranged substantially horizontally as shown. Within the receptacle 134 is a follower 135 connected by a rod 136 with a piston 137 in a cylinder 138. The cylinder 138 has inlets 139 and 140 whereby compressed air or other fluid under pressure may be supplied to the cylinder at either side of the piston so as to operate the same to move the follower. When bristles are being used from the receptacle 134 air or other fluid under pressure is being supplied to the cylinder 138 through the inlet 139 whereby to keep the follower against the bristles 133 and constantly urge them toward the feeding disc 132. The feed and the means for accomplishing the feed of the bristles 133 toward the discs 132 may be the same or substantially the same as that previously described in connection with the feed of the bristles 85 toward the discs 96 and 97.

If the bristles 85 in receptacle 61 are hair then the bristle 133 in receptacle 134 may be of German silver or brass or the like. The space between the teeth of the discs 132 are such as to receive about one-half of the material which will be received in the spaces between the respective teeth of the discs 96 and 97. Since the discs 132

overlap the discs 96 and 97 at the point 141 which is above the bristles 85 it will be seen that the teeth of discs 96 and 97 will be partially filled with the bristles 133 before the discs enter into the receptacle 61 to pick up some of the bristles 85.

Therefore, a mixture of bristles will be carried by the discs 96 and 97 toward the core 10 and secured to the core by the wire 46. Since the discs 132 are driven by the gearing described it will be apparent that these discs rotate with the discs 96 and 97. A strap member 142 is secured to the receptacle 134 as by a screw 143 and this strap member inclines downwardly across the open end of the receptacle 134 and between the discs 132 in a manner to prevent the bristles 133 being forced out of the receptacle on air being supplied to the cylinder 138 through the inlet 139.

It is to be understood that the capacity of the teeth of discs 132 as compared with the capacity of the teeth of discs 96 and 97 may be varied to suit various requirements. That is, more or less of the bristles 133 may be fed to increase or decrease the proportion as between bristles 133 and 85. When bristles 133 are being used, that is when a mixture is being used, the wire is secured to the core in the usual manner and the lever 54 may be used to draw off some wire from the spool 47 after the gear 99 is locked by the finger piece 100 as previously described, the finger piece being moved to inoperative position as against the stop pin 144 during the actual operation of the machine either when the machine is being used to fill a core with one kind of bristles or with a mixture.

Having thus described the invention, what is claimed is:

1. In a machine for filling spirally grooved brush cores, means for rotating a spirally grooved brush core, rotatable means for feeding bristles to the core, means for causing relative movement between the core and feeding means in a direction lengthwise of the core, a wire secured at one end to the core and fed by rotation of the core and serving to draw the intermediate portions of the bristles into the spiral groove of the core to secure the bristles to the core, and means whereby said wire rotates said bristle feeding means.

2. In a machine for filling spirally grooved brush cores, said machine including a filling station, a receptacle having a discharge at said station, a metering wheel at said station, means for rotating a brush core, means for causing relative movement between the core and metering wheel in a direction lengthwise of the core, said metering wheel arranged to take bristles from the discharge of said receptacle and deliver the bristles to the core, and means to drive the metering wheel.

3. In a machine for filling brush cores, a holder for a supply of wire, means for rotating a brush core, means for feeding bristles to the core, means for causing relative movement between the core and feeding means in a direction lengthwise of the core, said feeding means including a metering wheel, and the wire from said holder adapted to be passed about the metering wheel and secured to the core whereby as the core is rotated the wire is drawn off the metering wheel and rotates the same to cause it to feed bristles and as the wire is drawn onto the core it secures the said bristles to the core.

4. In a bristle feeding means for a brush core filling machine, a receptacle for bristles, a follower in the receptacle, cylinder and piston

- means to actuate the follower to cause it to press the bristles toward one end of the receptacle, and a bristle feeding means comprising a metering wheel arranged at said end of the receptacle and against which the bristles are pressed. 5

5. In a machine for filling spirally grooved brush cores, a base, a work holder on the base, means for rotating the work holder to rotate a core, a receptacle having a discharge opening, a metering wheel arranged to take bristles from said receptacle through such opening and deliver the bristles to said core, means for causing relative movement between the metering wheel and the core in a direction lengthwise of the core, a follower in the receptacle, and means to operate the follower to have it continually press the bristles in the direction of said discharge opening during the operation of filling a brush core. 10

10. 6. In a machine for filling spirally grooved brush cores, a base, a work holder on the base, means for rotating the work holder to rotate a core, a bristle feeding means comprising a metering wheel adapted to feed bristles to the core, means for causing relative movement between the feeding means and core in a direction lengthwise of the latter, means for supplying bristles to the metering wheel, a holder on said machine, a supply of wire supported by said holder, said wire carried about a portion of the bristle feeding means and secured to the core at one end of the groove thereof whereby as the core is rotated it will wind the wire in the groove of the core and draw the wire on the bristle feeding means to rotate the latter and feed the bristles to the core, and said bristle feeding means feeding bristles to the core beneath the wire whereby portions of the bristles are carried into the groove of the core and secured to the core by the wire. 15

15. 7. In a machine for filling spirally grooved brush cores, a base, a work holder on the base, means for rotating the work holder to rotate a core, a receptacle having a discharge opening, a metering wheel arranged to take bristles from said receptacle through such opening and deliver the bristles to said core, means for causing relative movement between the metering wheel and the core in a direction lengthwise of the core, a follower in the receptacle, means to operate the follower to have it continually press the bristles in the direction of the discharge opening during the operation of filling a brush core, a holder on said machine, a supply of wire supported by said holder, said wire secured to the core at one end of the groove thereof whereby as the core is rotated it will wind the wire in the groove of the core, and said metering wheel feeding said bristles to the core beneath the wire whereby portions of the bristles are carried into the groove of the core and secured to the core by the wire. 20

20. 8. In a machine for filling spirally grooved brush cores, a base, a work holder on the base, means for rotating the work holder to rotate a core, a receptacle having a discharge opening, a metering wheel adapted to feed bristles to the core, means for causing relative movement between the feeding means and core in a direction lengthwise of the latter, means for supplying bristles to the metering wheel, a follower in the receptacle having a discharge end positioned to supply bristles to the metering wheel, a follower in the receptacle, means to operate the follower to have it constantly press the bristles in the direction of the metering wheel 25

25. during the operation of filling a brush core, a holder on said machine, a supply of wire supported by said holder, said wire carried about the portion of the bristle feeding means and secured to the core at one end of the groove thereof whereby as the core is rotated it will wind the wire in the groove of the core and draw the wire on the bristle feeding means to rotate the latter and feed the bristles to the core, and said bristle feeding means feeding bristles to the core beneath the wire whereby portions of the bristles are carried into the groove of the core and secured to the core by the wire. 30

30. 9. In a machine for filling spirally grooved brush cores, a base, a work holder on the base, means for rotating the work holder to rotate a core, a bristle feeding means comprising a metering wheel to feed bristles to the core, means for causing relative movement between the feeding means and core in a direction lengthwise of the latter, means for supplying bristles to the metering wheel, a holder on said machine, a supply of wire supported by said holder, said wire carried about a portion of the bristle feeding means and secured to the core at one end of the groove thereof, means for tensioning the wire whereby as the core is rotated it will wind the wire in the groove of the core and draw the wire on the bristle feeding means to rotate the latter and feed bristles to the core, and said bristle feeding means feeding bristles to the core beneath the wire whereby portions of the bristles are carried into the groove of the core and the bristles secured to the core by the wire. 35

35. 10. In a machine for filling spirally grooved brush cores, a base, a work holder on the base, means for rotating the work holder to rotate a core, a bristle feeding means to feed bristles to the core, means for causing relative movement between the feeding means and core in a direction lengthwise of the latter, a holder on said machine, a supply of wire supported by said holder, means whereby as the core is rotated the wire is wound into the groove of the core, said bristle feeding means feeding bristles to the core with portions of the bristles under the wire whereby said portions of the bristles may be carried into the groove of the core by the wire and the bristles secured to the core by the wire, and a manually operable jacking wheel adapted to be operated to engage said wire and press the same inwardly of the groove. 40

40. 11. In a machine for filling spirally grooved brush cores, a base, a work holder on the base, means for rotating the work holder to rotate a core, a bristle feeding means to feed bristles to the core, means for causing relative movement between the feeding means and core in a direction lengthwise of the latter, means for supplying bristles to the feeding means, said means including a receptacle having a discharge opening positioned to deliver bristles to the bristle feeding means, a follower in the receptacle, means to operate the follower to have it press the bristles in the direction of the bristle feeding means, automatic cut-off means for stopping the machine when the supply of bristles in the receptacle is low, said follower having a groove in its bristle engaging surface, a pin adapted to be passed through said groove beneath the bristles to support the same under pressure while the follower is withdrawn to permit of the insertion of an additional supply of bristles into the receptacle between the pin and follower, and said pin adapted to be withdrawn when the new sup- 45

45. 50. 55. 60. 65. 70. 75.

ply of bristles is pressed against the pin by the follower.

12. In a machine for filling spirally grooved brush cores, a base, a work holder, a bracket mounting the work holder on the base, means for rotating the work holder to rotate a core, a bristle feeding means to feed bristles to the core, means for causing relative movement between the feeding means and core in a direction lengthwise of the latter, means pivotally mounting the bracket on the base whereby the bracket has two positions in one of which the core is disposed at the bristle feeding means and in the other of which the core is disposed laterally of the bristle feeding means, and means to secure the bracket in each of said positions.

13. In a machine for filling brush cores, a support for a hollow spirally grooved core, said support including a chuck engaging one end of the core for rotating the same, means extending outwardly from the chuck and rotatable therewith and disposed within the core, and said means being of a diameter to be engaged by the inner wall of the spiral groove of the core whereby to support the core and brace the same.

14. In a machine for filling a brush core with a mixture of bristles, means for rotating a core, means for feeding a mixture of bristles to the core, said last means including a pair of receptacles each adapted to receive different kinds of bristles, a metering wheel associated with one of said receptacles and adapted to take bristles from the same and deliver the bristles to the core, a metering wheel associated with the other of said receptacles and adapted to deliver bristles therefrom to the first metering wheel, said second metering wheel being of less capacity than the first metering wheel and arranged to deliver bristles to the first metering wheel in advance of the point where the first metering wheel receives bristles from its receptacle, means to drive the first metering wheel, and means whereby movement of the first metering wheel is imparted to the second metering wheel.

15. In a machine for filling a brush core with bristles, means for rotating a core, means for feeding bristles to the core as it is rotated, said last means including a receptacle, a metering wheel associated with the receptacle and mounted to take bristles from the same and deliver the bristles to the core, and means whereby the metering wheel is operated in synchronism with the movement of the core.

16. In a machine for filling a brush core with a mixture of bristles, means for rotating a core, means for feeding a mixture of bristles to the core, said last means including a pair of receptacles each adapted to receive a different kind of bristle, a metering wheel associated with one of said receptacles and adapted to take bristles from the same and deliver the bristles to the core, a metering wheel associated with the other of said receptacles and adapted to deliver bristles therefrom to the first metering wheel, and means within the respective receptacles and operating continuously during the filling of a brush core to press the bristles in the receptacles toward the respective metering wheels and into the spaces between the teeth of the wheels.

17. In a machine for filling spirally grooved brush cores, a holder for a supply of wire, means for rotating a spirally grooved brush core, means for feeding bristles to the core, means for causing relative movement between the feeding means and core in a direction lengthwise of the latter,

said feeding means including a metering wheel, the wire from said holder having one end secured to the core whereby as the core is rotated the wire is drawn into the spiral groove of the core, and said wire between the holder and the core adapted to drive the metering wheel as the wire is drawn by the core whereby to feed bristles to the core with the intermediate portions of the bristles disposed under the wire whereby the bristles will have their intermediate portions drawn into the groove in the core and will be secured to the core by the wire.

18. In a bristle feeding means for a brush core filling machine, a receptacle for bristles, a metering wheel partially entering one end of said receptacle, means whereby said wheel is rotated, a follower in the receptacle, and means including a cylinder and piston construction to actuate the follower to cause it to press the bristles toward and against the metering wheel.

19. In a machine for filling spirally grooved brush cores, a base, a work holder on the base, means for rotating the work holder and moving it to rotate a core and feed the core lengthwise, said machine including a filling station past which the core or work is moved, a vertically disposed receptacle for bristles at said station, a bristle feeding means for feeding bristles to the core from the upper end of said receptacle as the core is moved past the filling station, and said bristle feeding means including a metering wheel comprising a disc-like member toothed in its periphery and partially entering said receptacle.

20. In a machine for filling brush core, a base, a work holder on the base, means for rotating the work holder and moving it to rotate a core and feed the core lengthwise, said machine including a filling station past which the core or work is moved, a vertically disposed receptacle for bristles at said station, a bristle feeding means partially entering the upper end of said receptacle for feeding bristles therefrom to the core as the core is moved past the filling station, a guide member between the bristle feeding means and the core, and said member acting to guide the bristles from the feeding means to the core.

21. In a machine for filling spirally grooved brush cores, a base, a work holder on the base, means for rotating the work holder to rotate a core, a bristle feeding means to feed bristles to the core, means for causing relative movement between the feeding means and core in a direction lengthwise of the latter, means for supplying bristles to the feeding means, said means including a vertically disposed receptacle, said bristle feeding means partially entering the upper end of said receptacle and carrying bristles therefrom, a follower in the receptacle, and means to actuate the follower to have it press the bristles in the direction of the bristle feeding means.

22. In a machine for filling spirally grooved brush cores, a base, a work holder on the base, means for rotating the work holder to rotate a core, a bristle feeding means comprising a metering wheel to feed bristles to the core, means for causing relative movement between the feeding means and core in a direction lengthwise of the latter, means for supplying bristles to the metering wheel, said means including a receptacle having a discharge end positioned to supply bristles to the metering wheel, a follower in the receptacle, means to operate the follower to have it press the bristles in the direction of the metering wheel during the operation of filling a brush core, and said means including a piston and a cylinder and

means to apply a continuous pressure to the follower.

23. In a machine for filling spirally grooved brush cores, a base, a work holder on the base, means for rotating the work holder to rotate a core, a bristle feeding means comprising a metering wheel to feed bristles to the core, means for causing relative movement between the feeding means and core in a direction lengthwise of the latter, means for supplying bristles to the metering wheel, a holder on said machine, a supply of wire supported by said holder, said wire secured to the core at one end of the groove thereof whereby as the core is rotated it will wind the wire in the groove of the core, and said metering wheel feeding bristles to the core beneath the wire whereby portions of the bristles are carried into the groove of the core and the bristles are secured to the core by the wire.
24. In a machine for filling spirally grooved brush cores, a base, a work holder on the base, means for rotating the work holder to rotate a core, bristle feeding means comprising a metering wheel to feed bristles to the core, means for causing relative movement between the feeding means and core in a direction lengthwise of the latter, means for supplying bristles to the metering wheel, said means including a receptacle having discharge end positioned to supply bristles to the metering wheel, a follower in the receptacle, means to operate the follower to have it press the bristles in the direction of the metering wheel, said means including a piston, a cylinder in which the piston operates, and means to supply a fluid under pressure to the cylinder and at one side of the piston whereby to cause the follower to exert a continuous pressure on the bristles in the receptacle during the operation of filling a core, a holder on said machine, a supply of wire supported by said holder, said wire carried about a portion of the bristle feeding means and secured to the core at one end of the groove thereof whereby as the core is rotated it will wind the wire in the groove of the core and draw the wire on the bristle feeding means to rotate the latter and feed bristles to the core, and said bristle feeding means feeding bristles to the core with the intermediate portions of the bristles under the wire whereby said intermediate portions of the bristles are carried into the groove of the core and the bristles secured to the core.
25. In a machine for filling spirally grooved brush cores, a base, a work holder on the base, means for rotating the work holder to rotate a core, bristle feeding means comprising a metering wheel to feed bristles to the core, means for causing relative movement between the feeding means and core in a direction lengthwise of the latter, means for supplying bristles to the metering wheel, said means including a receptacle having a discharge end positioned to supply bristles to the metering wheel, a follower in the receptacle, means to operate the follower to have it press the bristles in the direction of the metering wheel, said means including a piston, a cylinder in which the piston operates, and means to supply a fluid under pressure to the cylinder and at one side of the piston whereby to cause the follower to exert a continuous pressure on the bristles in the receptacle during the operation of filling a core, a holder on said machine, a supply of wire supported by said holder, said wire secured to the core at one end of the groove thereof whereby as the core is rotated it will wind the wire in the groove of the core, and said bristle feeding means feeding
26. In a machine for filling spirally grooved brush cores, a base, a work holder on the base, means for rotating the work holder to rotate a core, bristle feeding means comprising a metering wheel to feed bristles to the core, means for causing relative movement between the feeding means and core in a direction lengthwise of the latter, means for supplying bristles to the metering wheel, a holder on said machine, a supply of wire supported by said holder, said wire secured to the core at one end of the groove thereof, means for tensioning said wire whereby as the core is rotated the wire will be wound into the groove of the core, and said metering wheel feeding bristles to the core beneath the wire whereby portions of the bristles are carried into the groove of the core and the bristles are secured to the core by the wire.
27. In a machine for filling spirally grooved brush cores, a base, a work holder on the base, means for rotating the work holder to rotate a core, bristle feeding means comprising a metering wheel to feed bristles to the core, means for causing relative movement between the feeding means and core in a direction lengthwise of the latter, means for supplying bristles to the metering wheel, a holder on said machine, a supply of wire supported by said holder, means whereby as the core is rotated the wire is wound into the groove of the core, and said metering wheel feeding bristles to the core with portions of the bristles under the wire whereby said portions of the bristles are carried into the groove of the core and the bristles secured to the core by the wire.
28. In a machine for filling spirally grooved brush cores, a base, a work holder on the base, means for rotating the work holder to rotate a core, a bristle feeding means to feed bristles to the core, means for causing relative movement between the feeding means and core in a direction lengthwise of the latter, a holder on said machine, a supply of wire supported by said holder, means whereby as the core is rotated the wire is wound into the groove of the core, means for tensioning said wire, and said bristle feeding means feeding bristles to the core with portions of the bristles under the wire whereby said portions of the bristles are carried into the groove of the core and the bristles secured to the core by the wire.
29. In a machine for filling spirally grooved brush cores, a base, a work holder on the base, means for rotating the work holder to rotate a core, a bristle feeding means to feed bristles to the core, means for causing relative movement between the feeding means and core in a direction lengthwise of the latter, a holder on said machine, a supply of wire supported by said holder, means whereby as the core is rotated the wire is wound into the groove of the core, means for tensioning the wire, said bristle feeding means feeding bristles to the core with portions of the bristles under the wire whereby said portions of the bristles may be carried into the groove of the core by the wire and the bristles secured to the core by the wire, and a manually operable jacking wheel adapted to be operated to engage said wire and assist the tensioning means by pressing the wire inwardly of the groove.
30. In a machine for filling spirally grooved brush cores, a work holder, means for rotating the work holder to rotate a core, a bristle feeding means to feed bristles to the core, means for

causing relative movement between the feeding means and core in a direction lengthwise of the latter, said bristle feeding means including a metering wheel, means for supplying bristles to the metering wheel, said means including a receptacle having a discharge opening positioned to deliver bristles to the metering wheel, a follower in the receptacle, means to operate the follower to have it continuously press the bristles in the direction of the bristle feeding means during the operation of filling a brush core, said means for operating the follower including a cylinder and a piston and means for supplying a fluid under pressure to the cylinder, automatic cut-off means for stopping the machine when the supply of bristles in the receptacle is low, said follower having a pair of spaced grooves in its bristle engaging surface, a pair of pins adapted to be passed through said grooves beneath the bristles to support the same under pressure while the follower is withdrawn from the bristles to permit of the insertion of an additional supply of bristles into the receptacle between the pins and the follower, and said pins adapted to be withdrawn when the additional supply of bristles is pressed against the pins by the follower.

31. In a machine for filling spirally grooved brush cores, a base, a work holder, means mounting the work holder on the base, means for rotating the work holder to rotate a core, a bristle feeding means to feed bristles to the core, means for causing relative movement between the feeding means and core in a direction lengthwise of the latter, and said means mounting the work holder being so mounted that it may be moved to swing the work holder and carry a filled brush core away from the bristle feeding means.

32. In a machine for filling spirally grooved brush cores, a base, a work holder, a bracket mounting the work holder on the base, means for rotating the work holder to rotate a core, a bristle feeding means to feed bristles to the core, means for causing relative movement between the feeding means and core in a direction lengthwise of the latter, and means pivotally mounting the bracket on the base whereby the bracket may be moved to dispose a filled brush core laterally of the bristle feeding means.

33. In a machine for filling brush cores, a support for a hollow spirally grooved core, said support including a chuck for rotating the core, and an externally smooth means passing through the core and engaged only by the inner wall of the spiral groove of the core whereby to support and brace the core and to be readily insertable into and removable from the core.

34. In a machine for filling a brush core with a mixture of bristles, means for rotating a core, means for feeding a mixture of bristles to the core, means for causing relative movement between the feeding means and core in a direction lengthwise of the latter, said feeding means including a pair of receptacles each adapted to receive different kinds of bristles, a metering wheel associated with one of said receptacles and adapted to take bristles from the same and deliver the bristles to the core, a metering wheel associated with the other of said receptacles and adapted to deliver bristles therefrom to the first metering wheel, and said second metering wheel being of less capacity than the first metering wheel and arranged to deliver bristles to the first metering wheel in advance of the point where the first metering wheel receives bristles from its receptacle.

35. In a machine for filling a brush core with a mixture of bristles, means for rotating a core, means for feeding a mixture of bristles to the core, said last means including a pair of receptacles and a metering wheel for each receptacle, and said metering wheels arranged adjacent one another whereby one wheel delivers to the other and the other delivers to the core. 5

36. In a machine for filling a brush core with bristles, said machine including a filling station, means for rotating and feeding a core past said station, means for feeding bristles to the core at the station, said last means including a receptacle, a metering wheel associated with the receptacle and adapted to take bristles from the same and deliver the bristles to the core, a follower in the receptacle, and fluid pressure operated means forcing the follower against the bristles to urge the latter against said metering wheel. 20

37. In a machine for filling a brush core with bristles, said machine including a filling station, means for feeding a core past said station, means for feeding bristles to the core at the station, said last means including a receptacle, a metering wheel associated with the receptacle and adapted to take bristles from the same and deliver the bristles to the core, and said metering wheel including a pair of spaced peripherally toothed disc-like members. 30

38. In a machine for filling a brush core with bristles, means for rotating a core, means for feeding bristles to the core, means for causing relative movement between the feeding means and core in a direction lengthwise of the latter, said feeding means including a receptacle, a metering wheel associated with the receptacle and adapted to take bristles from the same and deliver the bristles to the core, and fluid pressure operated means within the receptacle and operating continuously during the filling of a brush core to press the bristles toward the metering wheel. 35

39. In a machine for filling a brush core with bristles, means for rotating a core, means for feeding bristles to the core, means for causing relative movement between the feeding means and core in a direction lengthwise of the latter, said feeding means including a vertically disposed receptacle, a metering wheel associated with the receptacle and adapted to take bristles from the upper end of the same and deliver the bristles to the core, said metering wheel including a pair of spaced rigidly connected peripherally toothed disk-like members, and means within the receptacle and operating continuously during the filling of a brush core to press the bristles upward toward the metering wheel and into the spaces between the teeth of the wheel. 45

40. In a machine for filling a brush core with a mixture of bristles, means for rotating a core, means for feeding a mixture of bristles to the core, means for causing a relative movement between the feeding means and core in a direction lengthwise of the latter, said feeding means including a pair of receptacles each adapted to receive a different kind of bristle, a metering wheel associated with one of said receptacles and adapted to take bristles from the same and deliver the bristles to the core, a metering wheel associated with the other of said receptacles and adapted to deliver bristles therefrom to the first metering wheel, said second metering wheel being of less capacity than the first metering wheel and arranged to deliver bristles to the first metering wheel. 60

75

- tering wheel in advance of the point where the first metering wheel receives bristles from its receptacle, means within the respective receptacles and operating continuously during the filling of 5 a brush core to press the bristles in the receptacles toward the respective metering wheels, means to drive the first metering wheel, and means whereby movement of the first metering wheel is imparted to the second metering wheel.
- 10 41. In a machine for filling a brush core with a mixture of bristles, said machine including a filling station, means for feeding a core past said station, means for feeding a mixture of bristles to the core at the station, said last 15 means including a pair of receptacles each adapted to receive a different kind of bristle, a metering wheel associated with one of said receptacles and adapted to take bristles from the same and deliver the bristles to the core, a metering wheel 20 associated with the other of said receptacles and adapted to deliver bristles therefrom to the first metering wheel, said second metering wheel being of less capacity than the first metering wheel and arranged to deliver bristles to the first 25 metering wheel in advance of the point where the first metering wheel receives bristles from its receptacle, means to drive the first metering wheel, and means whereby movement of the first metering wheel is imparted to the second 30 metering wheel.
42. In a machine for filling spirally grooved brush cores, a base, a work holder on the base, means for rotating the work holder and moving it to rotate a core and feed the core lengthwise, 35 said machine including a filling station past which the core or work is moved, a bristle feeding means comprising a metering wheel at said station and adapted to feed bristles to the core as the core is moved past the filling station, said 40 metering wheel comprising a peripherally toothed disc-like member, means for supplying bristles to the metering wheel, said means including a receptacle having its discharge end positioned to supply bristles to the metering wheel, a follower 45 in the receptacle, means to operate the follower to have it press the bristles in the direction of the metering wheel, said means including a cylinder and piston and means to apply a continuous pressure to the piston during the operation 50 of filling a brush core, a holder on said machine, a supply of wire supported by said holder, said wire carried about a portion of the bristle feeding means and secured to the core at one end of the groove thereof whereby as the core 55 is rotated and fed it will wind the wire in the groove of the core and draw the wire on the bristle feeding means to rotate the metering wheel and feed bristles to the core, said bristle feeding means feeding bristles to the core with 60 the intermediate portions of the bristles under the wire whereby said intermediate portions of the bristles are carried into the groove of the
- core and the bristles secured to the core by the wire, tensioning means acting on the wire before it is passed about the bristle feeding means whereby to maintain the wire taut and cause the same to rotate the bristle feeding means and draw into the groove of the core, a jacking wheel, lever means to operate said wheel to press the same against a wire and press the wire tight into the groove in the core, automatic cut-off means for stopping the machine when the supply 10 of bristles in the receptacle is low, said follower having grooves in its bristle engaging surface, pins adapted to be passed through said grooves beneath the bristles to support the same under pressure while the follower is withdrawn to permit the insertion of additional bristles into the receptacle between the pins and follower, said pins adapted to be withdrawn when the new supply of bristles is pressed against them by the follower, and means mounting the core and work 15 holder whereby the core may be moved away from the bristle means when the core is filled and before the core is removed from the work holder.
43. In a machine for filling spirally grooved brush cores, a base, a work holder on the base, 20 means for rotating the work holder to rotate a core, means to feed bristles to the core, means for causing relative movement between the feeding means and the core in a direction lengthwise of the latter, means for supplying bristles to the 25 feeding means, said last means including a receptacle having a discharge opening positioned to deliver bristles to the feeding means, a follower in the receptacle, means to operate the follower to have it press the bristles in the direction of the bristle feeding means, and automatic 30 cut-off means for stopping the machine when the supply of bristles in the receptacle is low.
44. In a machine for filling brush cores, a base, a work holder on the base, means for rotating 35 the work holder to rotate a core, means for feeding bristles to the core, means for causing relative movement between the feeding means and the core in a direction lengthwise of the latter, means for supplying bristles to the feeding means, 40 said last means including a receptacle having a discharge opening positioned to deliver bristles to the feeding means, a follower in the receptacle, means to operate the follower to have it press the bristles in the direction of the bristle feeding means, said follower having a groove in 45 its bristle engaging surface, means adapted to be passed through said groove beneath the bristles to support the same under pressure while the follower is withdrawn to permit of the insertion 50 of an additional supply of bristles into the receptacle between the means and follower, and said means adapted to be withdrawn when the new supply of bristles is pressed against the means by the follower.
